UNITED STATES PATENT OFFICE

144,669

DESIGN FOR A SERVICE STATION ISLAND OR THE LIKE

Wilbur H. Adams, Erie, Pa., assignor to Erie Meter Systems, Inc., Erie, Pa., a corporation of Pennsylvania

Application June 1, 1945, Serial No. 119,846

Term of patent 14 years

(Cl. D13—1)

To all whom it may concern:

Be it known that I, Wilbur H. Adams, a citizen of the United States, residing at Erie, in the county of Erie and State of Pennsylvania, have invented a new, original, and ornamental Design for a Service Station Island or the like, of which the following is a specification, reference being had to the accompanying drawing, forming a part thereof.

The figure is a perspective view of a service station island showing my new design. The opposite side is similar in appearance to the side shown.

I claim:

The ornamental design for a service station island or the like, substantially as shown and described.

WILBUR H. ADAMS.
